US00D924260S

(12) **United States Design Patent** (10) Patent No.: **US D924,260 S**
 Cranfill (45) Date of Patent: ** Jul. 6, 2021

(54) **DISPLAY SCREEN OR PORTION THEREOF WITH GRAPHICAL USER INTERFACE**

(71) Applicant: **Apple Inc.**, Cupertino, CA (US)

(72) Inventor: **Elizabeth Caroline Cranfill**, San Francisco, CA (US)

(73) Assignee: **Apple Inc.**, Cupertino, CA (US)

(**) Term: **15 Years**

(21) Appl. No.: **29/721,164**

(22) Filed: **Jan. 17, 2020**
